DESIGN FOR A DISPLAY RACK

Melvin L. McLean, Fairbury, Nebr.

Application April 8, 1939, Serial No. 84,153

Term of patent 14 years

To all whom it may concern:

Be it known that I, Melvin L. McLean, a citizen of the United States, residing at Fairbury, in the county of Jefferson and State of Nebraska, have invented a new, original, and ornamental Design for a Display Rack, of which the following is a specification, reference being had to the accompanying drawing, forming part thereof.

I claim:

The ornamental design for a display rack, as shown.

MELVIN L. McLEAN.
